(57) **CLAIM**

I claim the ornamental designs for a microvaporizer cartridge, substantially as shown and described.

DESCRIPTION

FIG. 1 is a front perspective view of a microvaporizer cartridge while engaged in a microvaporizer;

FIG. 2 is a front perspective view of the microvaporizer cartridge;

FIG. 3 is a rear perspective view of the microvaporizer cartridge;

FIG. 4 is a top plan view of the microvaporizer cartridge, wherein the bottom plan view is identical to the top;

FIG. 5 is a right side view of the microvaporizer cartridge, wherein the left side view is a mirror image of the right side view;

FIG. 6 is a front view of the microvaporizer cartridge; and, FIG. 7 is a rear view of the microvaporizer cartridge.

The broken lines shown in the drawings illustrate an environment for the microvaporizer cartridge that form no part of the claimed design.
